UNITED STATES PATENT OFFICE

ARTHUR P. ARMINGTON, OF WILLOUGHBY, OHIO

TREAD LINK

Application filed July 21, 1932. Serial No. 623,708.

This invention relates to endless tread linkages of truss-forming or beam-forming type for employment as wheel substitutes in the running gear of slow-moving heavy-duty vehicles.

A linkage capable of so functioning is disclosed in Patent No. 425,600 issued April 15, 1890, to Edwards, and its manner of use is disclosed in Patent No. 1,458,962 issued June 19, 1923 to Athey; but the general type of link here contemplated is more similar to that shown in Patent No. 1,808,445 issued to me June 2, 1931.

In all of these linkages of the class described one of the functions is that the ground-engaging stretch of the linkage have beam characteristics, that is, be inflexible upwardly or inwardly between the wheels bearing on the ends of the stretch. From a consideration of the form of link shown in my said patent it will be observed that such flexing of the stretch is resisted by contact between adjacent links, first at the hinge means by which they are connected in the linkage, and secondly at the cooperating truss members upstanding from the ground-engaging shoe parts of the links.

It is highly desirable that the truss-forming stretch of linkage have an arch or bow outwardly or oppositely to the forces which it is to resist as a beam, and this arch is customarily provided by making the pitch spacing of the truss members slightly less than that of the hinge means, as will be appreciated by one familiar with the art. Obviously wear at these contacting parts will reduce the arch of the stretch. Hence to reduce such wear is highly important since by such reduction the flattening or collapse of the arch is correspondingly reduced.

Patent No. 1,854,013, issued April 12, 1932, to me and others, and Patent No. 1,862,617 issued to me June 14, 1932, show two arrangements whereby such wear is practically eliminated, and the latter of these patents and particularly its file history, exposes the theory of the causes of such wear and the consequent manner of its reduction.

The principal object of this invention is to

accomplish a similar ultimate result, by simpler and more inexpensive means.

Wear at the hinge means is reducible only to a limited extent because of the motion at the hinge joints as the links have relative motion thereabout when passing between bends and stretches. Another object of the invention is to provide that as this unavoidable wear takes place at the hinge connections, the arch will nevertheless be maintained by a novel functional relation between the truss members.

Further objects and advantages of the invention will be apparent from the following description taken in connection with the accompanying drawings, in which Figs. 1, 2 and 3 are plan view, end elevation and side elevation respectively of a link unit embodying the invention shown in ground-engaging position, as in a lower stretch of linkage, parts being broken away to show details of construction; and Fig. 4 is a diagrammatic view illustrative of the manner of functioning, proportions of the operative parts being exaggerated for better illustration.

With reference now to the drawings and particularly to Figs. 1-3 thereof, 1 is the shoe or pad part of the link having a generally flat ground-engaging surface 2. Above at its sides the shoe has rail surfaces 3; at one end the shoe has a pair of spaced lugs 4 and at its opposite end three similar lugs 5 arranged in staggered relation with the lugs 4.

The lugs 5 are provided with aligned openings 6 to receive a hinge pin 7 of round bar stock. The openings 6 may be cored and the relation between them and the hinge pin 7 is such that the pin may rotate. Retaining pins 8 are secured in the openings 6 of the end lugs 5 to position the hinge pin 7 endwise, yet allow its rotation.

The lugs 4 on the opposite end of the shoe likewise have aligned openings which may be bushed as at 9 to receive the hinge pin 7 of the next adjacent similar link in a linkage.

Thus it will be obvious that an endless tread linkage may be made up of a plurality of links similar to the one shown.

Upstanding from the shoe part 1 of the link is a pair of truss members. One of these

truss members is in the form of a pair of transversely spaced bracket members 10, having aligned openings 11 to receive and support a truss pin 12 transversely extending between the members 10 in elevated position above the shoe 1. The truss pin 12 is mounted for free rotation in its supporting openings 11, to allow a limited amount of rolling, as will be described, and the pin is positioned endwise therein by retaining pins 13 in a manner similar to that of mounting the hinge pin 7.

While the diametrical fit of the hinge pin 7 is desirably as tight as foundry and/or machine practice will allow without binding provided rotation of the pin is permitted, the diametrical fit of the truss pin 12 may be a looser one. These pins 7 and 12 must be permitted rotation in the functioning of the linkage, as will appear. Their mounting is what is known as of the floating type.

The truss pin 12 is approximately above one end of the shoe 1 and the truss members 10 extend at their base parts toward the opposite end of the shoe as at 14. Upstanding from the opposite end of the shoe is a co-operative truss member 15 having its base part 16 extending between the members 10. The upper extremity of the member 15 is in the form of a hook 17 having a concave cylindrical surface 18 substantially corresponding with the diameter of the truss pin 12. The surface 18 extends parallel with the truss pin, transversely of the link, substantially the distance of clearance between the faces of the brackets 10 adjacent the pin. The spacing between the center of curvature of the face 18 and the center of the hinge pin 7 is the same as that between the center of the truss pin 12 and that of the bushings 9. The spacing between the center of the face 18 and that of the truss pin 12 is preferably slightly less than that between the hinge pin openings on the opposite ends of the shoe of the link, so that a stretch of the linkage will have a slight curvature.

Thus the link includes a pair of truss members, one in arched form with the projecting part of the truss pin 12—that part extending between the brackets 10—constituting the central or bridge part of the arch, and the other a hook member adapted to cooperate with the bridge part of the arch of its next adjacent link.

Fig. 4 illustrates a stretch of linkage made up of a number of such links wherein the hinge and truss pins 7 and 12 are shown of exaggeratedly undersized diameter, as after a great deal of wear has occurred. It will be seen that the hook member of each link extends between the members 10 of the next adjacent link to engage the truss pin 12 supported by those members 10. Thus bending of the linkage in one direction is prevented, but the linkage is free to bend in

the opposite direction by folding of the hook members downwardly from their truss pins and between the brackets supporting the latter. It will also be observed that the rails 3 of the links form a substantially continuous pair of tracks, one on each side of the linkage. 70

The loading of forces on such a ground-engaging stretch of the linkage is illustrated by the downwardly directed arrows B and C at the ends of the stretch and the upwardly directed arrow A intermediate the ends of the stretch. In practice the forces B and C are of course set up by wheels running upon the tracks formed by the rails 3 and located at the bights of the linkage, and the force A by 80 the ground upon which the linkage is supported, bearing against the shoe surfaces 2.

It will be noted that on opposite sides of the force A the relative vertical displacement of adjacent links is in opposite directions. 85 The direction of motion of a vehicle supported upon the linkage shown Fig. 4, would be toward the left. Thus in the stretch of the linkage the force A may be considered as moving toward the left, as are the forces B 90 and C. As the force A passes from one link onto the next there is motion between the links at both the hinge pin 7 and the truss pin 12 of the joint.

The broken line 19 is intended to indicate 95 the relative disposition of the links in the stretch. In this line each relatively horizontal dot-dash line indicates the center line between hinge pin openings of one link, while each relatively short generally vertical line 100 indicates the displacement between two adjacent link ends. This displacement retains its direction until the force A is passed at which time the direction is reversed and it is thence maintained throughout the stretch. 105

Specifically, it is the object of this invention to reduce wear at the contacting truss-forming parts during the motion therebetween when this displacement change occurs.

The operation is quite simple. As the 110 force A progresses relative to the stretch of linkage, and adjacent links have relative motion at their joint, the corresponding hinge pin 7 and the truss pin 12 simply act as rollers between the parts which bear against them 115 so that there is no sliding friction between those parts.

The oppositely directed faces of the truss members between which the truss pins 12 bear, for transmitting the truss-forming stresses between links, will be noted as concavely curved. Consequently when adjacent links have relatively translatory motion generally vertically as when passing the force A, Fig. 4, such pair of links will be caused 125 relative angular motion about the hinge connection which joins them, in a direction to oppose the loading of the forces A, B and C on the stretch. In other words, the truss-forming parts of the adjacent pair of links 130

when the latter have relative vertical motion caused by looseness at their hinge pin, are drawn together by the bearing of the truss pin on their opposed concave faces so as to increase the arch of the stretch of linkage.

In Fig. 4, the pins being shown greatly undersized, considerable motion is indicated at the pins. However, in practice it will be appreciated that a good fit may be had between the pins and their bearing parts so that this motion will be actually very slight. Nevertheless, however close the fit, provided the fit allows rolling of the pins—that is, provided the fit is not tight—there will be some motion between links as the force A is passed. This motion, however slight, will be accompanied by the described roller action of the hinge and truss pins, whereby sliding bearing is substantially eliminated.

When a plurality of links as described are assembled in an endless linkage to form a track, and the track is mounted upon a pair of wheels, with bends about the wheels and stretches therebetween,—all as is customary in the art—and the entire assembly is put into service, there will be relative angular motion. This motion will cause sliding bearing upon the hinge pins as the links pass between bends and stretches of the linkage, so that the fit at the hinge pins will gradually become looser. Obviously the looser the fit at the hinge connections the more vertical motion will take place between links as the force A, Fig. 4, is passed. The greater such relative vertical motion, however, and the more consequent vertical motion between cooperative truss members upon the common truss pin therebetween, the more will adjacent links be caused relative angular motion about their hinge connection in a direction to increase the arching relation therebetween.

What I claim is:

1. An endless tread linkage composed of articulate links, each adjacent pair of links having rail-carrying ground-engaging shoe parts with hinge means connecting their adjacent ends, truss members upwardly extending from said shoe parts and having oppositely directed bearing faces for transmitting truss-forming stresses between said links, and roller means arranged to be effective between said faces to provide wear-preventing characteristics for their relative translatory motion, permitted by lost motion at said hinge connection due to wear when said links are operating in a truss-forming stretch of linkage.

2. A tread linkage composed of articulate links, each adjacent pair of links having rail-carrying ground-engaging shoe parts with hinge means connecting their adjacent ends, truss members upwardly extending from said shoe parts and having oppositely directed bearing faces for transmitting truss-forming stresses between said links, and roller means

arranged to be effective between said faces to provide antifriction characteristics for their relative translatory motion, permitted by looseness at said hinge connection, at least one of said faces being concavely curved whereby upon relative translatory motion of said links permitted by looseness at said hinge connection when said links are operating in a truss-forming stretch of linkage, said links will be caused relative angular motion about said connection in a direction to oppose the loading on said stretch.

In testimony whereof I hereby affix my signature.

ARTHUR P. ARMINGTON.
